UNITED STATES PATENT OFFICE.

GEORGE F. STICKNEY, OF ALBANY, NEW YORK.

SIPHON SPILLWAY.

1,405,071.

Specification of Letters Patent. Patented Jan. 31, 1922.

Application filed February 18, 1921. Serial No. 446,052.

To all whom it may concern:

Be it known that I, GEORGE F. STICKNEY, a citizen of the United States, residing at Albany, in the county of Albany and State of New York, have invented certain new and useful Improvements in Siphon Spillways; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to siphons used in dams, spillways or waste weirs, for the purpose of discharging water and particularly to methods of priming siphons which have their throats wholly or in part below the 20 high, or flood water, stage controlled by said siphons.

In siphon spillways heretofore constructed, the siphon consists of an inverted U shaped conduit through a dam, with its 25 throat entirely above the low water level; an up-stream leg that extends from the throat to the up-stream face of the dam, terminating in an inlet below the water level; a down-stream leg extending from the throat to an outlet in the down-stream face of the dam and an air vent to the 30 throat, that pierces the up-stream face of the dam at about the low water level.

In such siphons priming is effected by a 35 raise in the water level above the dam, sufficient to seal the siphon against the entrance of air and to provide a flow that will displace and carry out the air confined therein, after which the full siphonic flow 40 is established.

When the water level above the dam is drawn down, sufficiently to uncover the air vent, air is admitted to the throat of the siphon and this stops the siphonic action so 45 that the flow ceases.

It is desirable, for well known reasons, to so design the dam or spillway as to make the difference between the high and low stages of the pool above the dam as small 50 as possible and, for reasons of economy, it is desirable to make the capacity of the

spillway as large as possible, thus reducing to a minimum the length of the structure necessary to pass a given volume of water.

When the cross-sectional area of the 55 siphon is large the throat is high and a considerable raise in the water level will be necessary in order to prime the siphon.

To obviate this difficulty it is necessary to provide special means for priming 60 siphons of large dimensions, which will operate automatically with a slight raise in the water level above the dam and to provide such means is the object of my invention.

15 The action of automatic siphons, as heretofore built, is clearly shown by Patent 991,907, granted to George F. Stickney May 9, 1911 and Patent 1,083,995, granted to William Russell Davis and George F. 70 Stickney, January 13, 1914.

This specification, with accompanying drawings, describes a distinctly new method of constructing a siphon spillway, as heretofore explained, by which the siphon will 75 be primed and put in operation with a less raise in the water level above the spillway and it is applicable to siphons of larger size than those heretofore considered.

The new form of construction consists 80 in introducing a break in the plane of the back-wall of the down-stream leg of the siphon, such that the stream of water flowing through the leg will be deflected so that a jet of water is formed which jumps 85 across the leg and impinges against the far wall and, in doing this, makes a diaphragm of water in the down-stream leg.

Priming is effected when there is a slight 90 raise in the water level above the spillway, sufficient to seal the throat of the siphon against the entrance of air through the up-stream leg or the air vent, and to produce a flow of water through the siphon.

Water spills through the throat of the 95 siphon and flows down the down-stream leg to the break in the plane of the back-wall where it is deflected, a jet is formed which jumps across the leg and impinges against the far wall making a diaphragm of water 100 in the down-stream leg that seals the upper portion of the siphon against the entrance

of air from below the jet, thus isolating a volume of air that is entrapped in the upper part of the siphon.

The jet of water, in impinging against the far wall of the down-stream leg, breaks into foam and becomes impregnated with air that is in contact with its upper surface.

This air is carried away by the flowing stream and is thus abstracted from the upper portion of the siphon.

The air remaining in the upper part of the siphon expands and, by doing so, is under less than atmospheric pressure so that the air pressure on the free water surface above the spillway forces the water to a higher level in the throat of the siphon than the stream outside; the depth of the water overflowing the throat increases; the jet of water in the down-stream leg is enlarged and has greater capacity for removing air.

This action progresses until the air enclosed in the upper part of the siphon is entirely removed, the siphon is primed and the full flow is established.

Referring to the drawings, in which like parts are similarly designated, Figure 1 is a section of a dam, taken through a siphon which has an inclined down-stream leg and which has a high throat, the lower edge of which is to be placed, approximately, at the low water stage above the dam, with a break in the plane of the back-wall of the down-stream leg, made by curving the back-wall outward so as to form an off-set, the break being located at sufficient distance below the throat level to insure that the water will acquire the velocity necessary to jump across the leg.

Figure 2 is a section of a dam, taken through a siphon which has an inclined down-stream leg and which has a high throat, the lower edge of which is to be placed, approximately, at the low water stage above the dam, with a break in the plane of the back-wall of the down-stream leg made by curving the surface outward with a reversing curve so as to form an off-set, the break being located at sufficient distance below the throat level to insure that the water will acquire the velocity necessary to jump across the leg.

Figure 3 is a section of a dam, taken through a siphon which has a vertical down-stream leg and which has a high throat, the lower edge of which is to be placed, approximately, at the low water stage above the dam, with a break in the plane of the back-wall of the down-stream leg formed by curving the back-wall outward so as to make an off-set, the break being located at sufficient distance below the throat level to insure that the water will acquire the velocity necessary to jump across the leg.

Figure 4 is a section of a dam, taken through a siphon which has a vertical down-stream leg and which has a high throat, the lower edge of which is to be placed, approximately, at the low water level above the dam, with a break in the plane of the back-wall of the down-stream leg made by curving the surface outward with a reversing curve so as to form an off-set in the leg, the break being located at sufficient distance below the throat level to insure that the water will acquire the velocity necessary to jump across the leg.

Figure 5 shows the construction at the outlet of a siphon when such outlet discharges high up on a dam, or where it is not necessary that the outflowing water shall issue in a horizontal direction.

These figures indicate the siphons to be constructed of masonry, preferably of concrete, though any suitable material may be used in their construction.

Referring to Figs. 1 and 3; 1 is the upstream face of the dam; 2 is the down-stream face; 3 is the top and 4 is the bottom, which is to rest on the customary foundations; 5 is an air vent, at about the low water plane; 6 is the inlet, placed below the low water stage; 7 is the up-stream leg; 8 is the throat; 9 is the down-stream leg; 10 is the outlet, flared upward somewhat so that air bubbles in the water will travel outward, in case the outlet is submerged; 11 is the break in the plane of the backwall of the down stream leg, made by a simple curve and forming an off-set; 13 is the jet of water and the diaphragm in the down-stream leg which seals the leg against the entrance of air from below and removes the air enclosed in the siphon above the jet; 14 is the high water surface above the dam; 15 is the water surface below the dam, located some distance below where the jet strikes the outer wall of the down-stream leg.

Referring to Figs. 2 and 4; 1 is the upstream face of the dam; 2 is the down-stream face; 3 is the top and 4 is the bottom, which is to rest on the customary foundations; 5 is an air vent at about the low water stage; 6 is the inlet, placed below the low water stage; 7 is the up-stream leg; 8 is the throat; 9 is the down-stream leg; 10 is the outlet, flared upward somewhat so that air bubbles in the water will travel outward, in case the outlet is submerged; 12 is the break in the plane of the back-wall of the down-stream leg, made by a reversing curve and forming an off-set; 13 is the jet of water and the diaphragm in the down-stream leg which seals the leg against the entrance of air from below and removes the air enclosed in the siphon above the jet; 14 is the high water surface above the dam; 15 is the water surface below the

dam, located some distance below where the jet strikes the outer wall of the down-stream leg.

Referring to Fig. 5, 2 is the down-stream face of the dam; 9 is the down-stream leg; 10 is the outlet; 12 is a break in the plane of the back-wall of the down-stream leg; 13 is the jet of water and the diaphragm in the down-stream leg.

10 The action of the siphons shown in Figs. 1 and 3 is as follows:—

When the water surface above the dam, 14 raises so as to submerge the air vent, 5, water flows up the up-stream leg, 7, 15 through the throat, 8, and down the inside of the down-stream leg, 9, to the break in the plane of the back-wall, 11, having acquired considerable velocity when it reaches the latter point, where it is deflected by 20 the curve and forms the jet, 13, which jumps across the down-stream leg, 9, and forms a diaphragm in the leg that seals it against the entrance of air from below the jet.

This jet, 13, impinges against the outer 25 wall of the down-stream leg, 9, breaks into foam and becomes impregnated with air in contact with its upper surface which air is carried away by the flowing stream and is thus abstracted from the upper part of the 30 siphon.

As the enclosed air is removed the portion remaining in the siphon is rarefied and its pressure is reduced to below that of the atmosphere.

35 The atmospheric pressure on the free water surface, 14, forces the water up to a higher level in the throat, 8, the depth of the over-flowing stream increases both in volume and in capacity for removing the enclosed air 40 at the jet, 13.

This action progresses until the siphon is completely filled with water, priming is effected and the full siphonic flow is established.

45 The action of the siphons shown in Figs. 2 and 4 is as follows:—

When the water surface above the dam, 14, raises so as to submerge the air vent, 5, water flows up the up-stream leg, 7, through 50 the throat, 8, and down the inside of the down-stream leg, 9, to the break in the plane of the back-wall, 12, having acquired considerable velocity when it reaches the latter point, where it is deflected by the curve and 55 forms the jet, 13, which jumps across the down-stream leg, 9, and forms a diaphragm in the leg that seals it against the entrance of air from below the jet, 13.

This jet, 13, impinges against the outer 60 wall of the down-stream leg, 9, breaks into foam and becomes impregnated with air in contact with its upper surface which air is carried away by the flowing stream and is

thus abstracted from the upper part of the siphon.

65

As the enclosed air is removed the portion remaining in the siphon is rarefied and its pressure is reduced to below that of the atmosphere.

The atmospheric pressure on the free water 70 surface, 14, forces the water up to a higher level in the throat, 8, the depth of the over-flowing stream increases both in volume and in capacity for removing the enclosed air at the jet, 13.

75

This action progresses until the siphon is completely filled with water, priming is effected and the full siphonic flow is established.

What I claim as my invention and desire 80 to secure by Letters Patent is:—

1. A siphon spillway for dams, waste weirs and the like, comprising an inverted substantially U shaped conduit with unequal legs the shorter leg opening through the up-stream face of the structure at a point below the normal low water level, the longer leg opening through the down stream face at the desired point of discharge; and means in said longer leg for causing a stream of 90 water flowing down one side of said leg to be projected across and to seal said leg with a diaphragm of water.

85

2. A siphon spillway for dams, waste weirs and the like, comprising an inverted substantially U shaped conduit with unequal legs, the shorter leg opening through the up-stream face of the structure preferably at a point some distance below the normal low water level and the longer leg opening 100 through the down stream face at the desired point of discharge; means in said longer leg for causing water flowing down one side thereof to be projected across and to seal said leg with a diaphragm of water; and an 105 air vent adapted to admit air to the throat of the siphon when the water on the up-stream side of the structure is below the normal low water level.

95

3. A siphon spillway for dams, waste weirs and the like, comprising an inverted substantially U shaped conduit with unequal legs the shorter leg opening through the up-stream face of the structure at a point below the normal low water level, the longer leg 115 opening through the down stream face at the desired point of discharge and a curved ledge formed in said longer leg and adapted to deflect a stream of water flowing down one side thereof and cause it to be projected 120 across said leg so as to form a diaphragm of water and seal said leg against air from below.

110

4. In a siphon spillway for dams, waste weirs and the like, an inverted and substantially U shaped conduit leading from a point 125

below the normal low water level on the upstream side of the structure to the desired point of discharge on the downstream side thereof; an air vent adapted to admit air to the throat of the siphon conduit when the water on the upstream side is below the normal low water level; and means formed in the discharge leg of said conduit adapted to deflect water flowing down one side thereof 10 and cause it to be projected across and to

seal said conduit by forming therein a water diaphragm and substantially as shown and described.

In testimony whereof I have affixed my signature in the presence of two witnesses. 15
